UNITED STATES PATENT OFFICE.

JOHN EARL BUCH, OF YORK, PENNSYLVANIA.

MECHANICALLY-OPERATED SETTLING DEVICE.

1,319,511.

Specification of Letters Patent.

Patented Oct. 21, 1919.

Application filed February 18, 1918. Serial No. 217,973.

To all whom it may concern:

Be it known that I, JOHN EARL BUCH, a citizen of the United States, residing at York, in the county of York and State of Pennsylvania, have invented certain new and useful Improvements in Mechanically-Operated Settling Devices, of which the following is a specification.

One object of my invention is to provide a mechanically operated device for jolting or settling down in a compact or solid mass granular material, such as sand, cement, etc., or in fact any material which consists of separate particles or pieces.

Another object is to make my invention of simple and durable construction and so that it will take comparatively little power to operate it.

These objects, and other advantageous ends which will be described hereinafter, I attain in the following manner, reference being had to the accompanying drawings in which—

Figure 1 is a top plan view of a device setting forth one embodiment of my invention,

Fig. 2 is an end elevation of Fig. 1,

Fig. 3 is a side elevation of the device shown in Figs. 1 and 2,

Fig. 4 is a sectional view taken on the line 4—4 of Fig. 1,

Fig. 5 is a fragmentary perspective view showing certain of the parts in a different position from that illustrated in Figs. 1 to 35 4, inclusive, and

Fig. 6 is an end elevation of similar nature to Fig. 2 but including a modification of certain of the elements.

Referring to Figs. 1 to 5, inclusive, of the drawings, 1 represents a base structure which may be made in the form of a hollow frame having a flat top 2 upon which normally rests a movable support 3. This support 3 may be in the form of a table or platform, as illustrated, and I have shown a flask, tray, or other container 4 resting on said movable support, and for example may be considered as filled with sand for molders or foundry use and which it is desired to jolt or settle into a more compact or solid form. The base structure 1 has two extensions 5 and these extensions at their outer ends form bearings for a shaft 6, said shaft having a pulley 7 thereon by which it is rotated, and also includes two cranks 8.

Two fulcrumed members 9 are positioned at opposite ends of the base structure and, as illustrated, are in the form of double ended levers which are pivoted to the base structure 1, as illustrated at 10. The levers 9 have their ends 11 included in the planes of movement of the respective cranks 8 and each of the cranks 8 is preferably provided with an anti-friction roller 12 adapted to engage the upper edge surface 65 of the ends 11 on the respective levers 9.

The opposite ends of the levers 9 are pivotally connected at 13 to links 14, said links being pivotally connected at 15 to opposite ends of the movable support 3. 70

The movable support 3 has guiding rods or plungers 16 depending therefrom and adapted to slide within vertical slideways 17 provided by the base structure 1.

Considering that the shaft 6 rotates in the direction of the arrow shown in Fig. 2 and that the movable support 3 is in its normal position, resting on the base structure 1, the operation is as follows: The cranks 8 will straddle the ends 11 of the respective levers 9 until the anti-friction rollers 12 engage the top edges of said lever ends 11, such position being illustrated in Figs. 1 to 4, inclusive. A continued movement of the shaft 6 in said direction will cause the cranks to move the ends 11 of the levers 9 downwardly on the pivotal fulcrums 10 and at the same time the opposite ends of the levers 9 will be raised to effect the raising of the movable support 3, the latter being 90 guided during its raised movement by the plungers 16 within the slideways 17. This raising of the movable support 3 will continue until the levers 9 have been moved into such position that the cranks will free 95 or pass by the ends 11 after which the movable support 3 and the tray 4 will fall by gravity until said movable support is stopped by engagement with the upper surface of the base structure 1. This sudden 100 stopping of the movable support will cause the material within the container 4 to be jolted and settled down into a compact mass and it will be noted that the extent of this settling of the material within the container 4 can be varied according to the number of times that the movable support 3 is 105 permitted to fall.

It will be further noted that for each rotation of the shaft 6 the levers 9 will be 110

actuated and freed by the cranks 8 so that during the time when the levers 9 are not under control of the cranks 8 the movable support will have time to fall, as above described.

In the construction shown in Fig. 6, instead of a link connection between the pivots 15 and 13, as described in connection with Figs. 1 to 5, inclusive, I provide the opposite 10 ends of the movable support 3 with anti-friction rollers 18 so that the ends 19 of the levers 9 engage the bottom of the peripheral surfaces of these rollers and thereby effect the raising of the movable support 3. Also 15 in this construction I provide a stop 20 under each end 19 of the levers 9 so that when the levers are not under the control of the cranks 8 they can fall and rest upon the stops 20. In all other respects the construction 20 shown in Fig. 6 is similar to that described in connection with Figs. 1 to 5, inclusive, and I have, therefore, given similar parts corresponding reference numerals.

Furthermore, while I have illustrated but 25 one end view of the modification shown in Fig. 6, it will be understood that the opposite end of the device is similarly constructed and includes a stop 20 and an anti-friction roller 18.

30 My invention is well adapted for use in foundries for the making of molds for castings or cores and the sand can be settled down to the desired compactness. Also my invention is well adapted for use in factories 35 or manufacturing plants of various types where articles, such for example as bullets or shot, are required to be settled within shell casings, etc., and for many other purposes.

While I have described my invention as 40 taking a particular form, it will be understood that the various parts of my invention may be changed without departing from the spirit thereof, and hence I do not limit myself to the precise construction set forth, 45 but consider that I am at liberty to make such changes and alterations as fairly come within the scope of the appended claims.

Having thus described my invention, what 50 I claim as new and desire to secure by Letters Patent is:

1. In a device of the character described, a rotatable shaft having an integral crank thereon forming an interruption in the axial portion of the shaft; a movable support; 55 and a fulcrumed lever, said crank during the rotation of the shaft being initially operative to straddle one end portion of said lever to move said lever to raise the movable support, said crank during a por-

tion of its continued movement being adapted to free said end of the lever to permit the movable support to fall by gravity, substantially as described.

2. A device of the character described including a rotatable shaft having an integral crank thereon located within its length and forming an interruption in the axial portion of the shaft; a movable support; and a fulcrumed lever, said crank during the rotation of the shaft being initially operated to 65 straddle one end portion of said lever to move said lever to raise the movable support, said crank during a portion of its continued movement being adapted to free said end of the lever to permit the movable support to fall by gravity, substantially as described. 70

3. In a device of the character described, a rotatable shaft having a crank thereon forming an interruption in the axial portion 80 of the shaft; an anti-friction roller on the portion of said crank which is remote from the axis of said shaft; a movable support; and a fulcrumed lever, said crank during the rotation of the shaft being initially 85 operative to straddle one end portion of said lever to permit said anti-friction roller to engage said lever and to move said lever to raise the movable support, said crank during a portion of its continued movement 90 being adapted to free said end of the lever to permit the movable support to fall by gravity, substantially as described.

4. A device of the character described including a rotatable shaft having a plurality 95 of integral cranks thereon forming interruptions in the axial portion of the shaft; a base structure; a plurality of fulcrumed levers; and a movable support normally resting on the base structure and adapted to 100 be raised by said fulcrumed levers when the latter are moved on their fulcrums, said cranks on the shaft being respectively adapted to straddle said levers and move them on their fulcrums to raise said support, said levers being of such length as to 105 be freed by said cranks after they have moved a certain distance to permit the movable support to fall by gravity upon said base structure, substantially as described.

In testimony whereof I have signed my name to this specification in the presence of two subscribing witnesses.

JOHN EARL BUCH.
